UNITED STATES PATENT OFFICE.

JOHN E. LEWIS, OF AVENUE, PENNSYLVANIA, ASSIGNOR OF THREE-FIFTHS TO ALLEGHENY STEEL AND IRON COMPANY, OF PITTSBURG, PENNSYLVANIA, A CORPORATION OF PENNSYLVANIA.

MACHINERY FOR PICKLING PLATES FOR COATING WITH TIN, &c.

SPECIFICATION forming part of Letters Patent No. 717,585, dated January 6, 1903.

Application filed February 19, 1902. Serial No. 94,796. (No model.)

To all whom it may concern:

Be it known that I, JOHN E. LEWIS, a citizen of the United States, residing at Avenue, in the county of Allegheny and State of Pennsylvania, have invented or discovered new and useful Improvements in Pickling Mechanism, of which the following is a specification.

The figure shows an elevation of my invention with parts in vertical section.

My invention relates to improvements in machinery for pickling or preparing plates for being coated with tin or other coating material.

15 My apparatus is constructed with a support consisting of a vertical cylinder 1. A hollow piston 2 reciprocates in the cylinder. The upper end of the piston-rod 3 works in the guide 4, which, with the cylinder 1, holds 20 the piston in a vertical position. Pivoted in the vertical slot 5 in the piston-rod is a rocking beam 6, having arc-shaped ends 7 7. Pickling-crates 8 8 are suspended from the beam by means of hooks 9 9, which catch over the 25 top of the arc-shaped ends and to which chains or cables 10 10 connect the crates.

Extending beyond the ends 7 7 of the beam 6 are arms 11 11, to which are pivoted clutch-blocks 12 12, provided with counterbalancing- 30 weighted arms 13 13, holding the blocks in the position shown on the drawing whatever the position of the beam.

14 is a rotating shaft carrying the crank 15, connected by the link 16 to the upper jaw 16' 35 of the clutch 17. The clutch is in the form of a pair of tongs, whose members 18 and 19 are pivotally connected at 20. The jaws of the clutch have inwardly-turned lugs 21, that engage the inner sides of the clutch-blocks.

40 The handles of the clutch extend downwardly within convenient reach of the operator and are locked together in any approved manner, as by the pin 22 passing through aligned holes.

Extending vertically below the beam and 45 secured thereto is an arm 23, held rigidly by the braces 24 24. The lower end of the arm 23 is provided with a wedge-shaped block 25.

From the hollow of piston 2 a vertical opening 26 leads into the slot 5. Working within

said piston and opening is a locking-piston 50 27, having at its top a Y-shaped opening 28 to receive the block 25.

The drawing represents the apparatus in its working position. The rotating shaft 14 causes the beam 1 to oscillate and the crates 55 suspended on the chains 10 10 to be agitated in the tanks. When the plates have been sufficiently treated, the clutch 17 is freed from the clutch-block 12 and fluid is admitted below the pistons 2 and 27, causing the 60 latter on account of its relative lightness to rise first and lock the beam in its horizontal position. After piston 27 has been fully elevated piston 2 rises, carrying the crates out of the tanks. The beam is then swung aside 65 and the chains relieved of their loads. I may take off one load, leaving the other load on, or I may load one end of the beam before loading the other; but in either case the beam remains horizontal. 70

My invention is not limited to pickling, but is applicable to various uses where it is desirable to lock a beam from oscillation.

Having described my invention, what I claim is— 75

1. In a pickling mechanism, a beam, means for oscillating the beam, means for raising the beam, and means movable relatively to the raising means for locking the beam from oscillation. 80

2. In a pickling mechanism, an oscillating beam, means for raising the beam, means detachable therefrom for oscillating the beam, and means for locking the beam from oscillation. 85

3. An oscillating beam, means for raising and oscillating the same, and means distinct and separate from the oscillating means for locking the beam from oscillation.

4. A beam and means for oscillating it, and telescopic hydraulic means for raising the beam and locking it from oscillation, said locking means being distinct and separate from the said oscillating means. 90

5. A beam and means for oscillating it, power mechanism for raising the beam and means operated by the same power that raises the beam for locking the beam from oscillation. 95

tion, said locking means being distinct and separate from the said oscillating means.

6. In a pickling mechanism, an oscillating beam, plate-holders carried thereby, a clutch-block on the beam, means for raising the beam, a rotary shaft, a clutch engageable with the clutch-block and means connecting the clutch and shaft.

7. A beam, a balanced pivoted clutch-block

thereon, a clutch therefor having jaws into which the block is receivable.

Signed at Tarentum this 4th day of February, 1902.

JOHN E. LEWIS.
